CLAIM

The ornamental design for a surfboard storage strap, as shown and described.

DESCRIPTION

FIG. 1 is a front elevational view of a surfboard storage strap showing my new design; FIG. 2 is a left side elevational view thereof, the right side being a mirror image of that shown; FIG. 3 is a rear elevational view thereof; and, FIG. 4 is a left side elevational view thereof, shown in the manner in which it would be used to support a surfboard, with the broken-line disclosure of a hook being for illustrative purposes only, and forming no part of the claimed design.
